Des. 1069

Edwin Gomez, of New York, N. Y.
Letters Patent No. 1069. Dated Nov. 30, 1858.

The schedule, referred to in these Letters Patent and making part of the same.

To all whom it may concern:

Be it known that I, E. Gomez, of the City, County, and State of New York, have invented a new design for combined wrought and cast iron railings, and I do hereby declare that the following is a full, clear, and exact description thereof, reference being had to the accompanying drawings making part of this Specification.

The object of my said design was to produce a series of ornaments for a complete panel for a railing so that by multiplying the numbers of panels a railing of any desired length could be produced, the said ornaments to be cast onto wrought iron rods previously bent and held in the mold so that in casting the said ornaments they should unite and bind together the said wrought iron rods.

In the accompanying drawing a. a. represent two standards rods forming the main frame work of one panel of a railing the ends of which may be either inserted and riveted or otherwise secured in the top and bottom rails b. b. or the said top and bottom rails may be cast onto the ends of any desired number of such standards according to the length of the rail desired to be produced; but this makes no part of my invention.

Near each end of each of these standards, I cast a

D.S. 1069

bottom c, to form the base and cap to the said standards. At or about the middle of the length, the two standards are bent outward in the form of a segment of a circle, or nearly so, as at d, d, and at each junction of the said curvature with the straight part of the standards I cast an ornament such as a flower and leaves e, e, e, e, or stem and leaves, so that the said four ornaments shall form a main middle ornament of greater diameter than the panel and of a circular form having a central rosette f, cast onto curved rods f, f, connected with the four ornaments e, which are cast theron as well as on the standards. Each of the ornaments e has a short stem g, projecting inward to give the appearance of continuity to the circular form of the middle ornament.

Near each end of the panel there is a like compound ornament h, and h' formed by the combination of separate ornaments that are united together and bind together the standard rods, but these instead of being completed as the middle ornament and as represented is only partial, as represented, the rosette h having only one connection with each standard instead of two.

From the foregoing it will be seen that I have produced a design to form a panel for railings composed of a series of separate bent wrought iron rods and cast ornaments so combined as to unite the several pieces of wrought iron by the act of casting on the ornaments, which panels may be so multiplied and connected together by a top and bottom rail as to produce a railing of any desired length.

I do not claim forming railings by casting ornaments on wrought iron rods thereby binding together the wrought iron rods as this has long been known, nor do I claim the configuration of the separate ornaments of which the said design is composed, as these are quite new.

What I claim as my invention and desire to secure by letters patent as a design for railings is the composition or combination of the several cast ornaments and curved rods and standards, united and producing an ornamental panel of the configuration, substantially as specified.

Witnesses.
